CIRCUIT INTERRUPTER

Louis E. Sauer, Sharon, Pa., assignor to Westinghouse Electric & Manufacturing Company, East Pittsburgh, Pa., a corporation of Pennsylvania

Application July 20, 1938, Serial No. 220,205

15 Claims. (Cl. 200—147)

This invention relates to circuit interrupters and more particularly to improvements in arc extinguishing devices for circuit interrupters of the air break type.

The general practice heretofore employed in power distribution systems involved almost exclusively the use of a substation building for housing the various pieces of equipment such as transformers, lightning arresters, high and low voltage circuit interrupters, various relays and other automatic control apparatus. It also was customary to distribute the several pieces of electrical equipment about the building which required considerable space. Circuit breakers of the air break type for protecting the lower voltage side of transformers are preferred over oil circuit breakers in installations of this kind due to the freedom of the air breaker from fire hazard during severe interrupting operations. However, for this type of service the air breaker must utilize an arc extinguishing device that will suppress flame during a circuit interrupting operation to such an extent as to prevent injury to adjacent pieces of apparatus. The desirability of eliminating the substation building and housing the entire substation equipment in a single metallic enclosure only slightly larger than the tank required for the power transformer, at once becomes apparent due to the great saving in space and the initial cost of construction.

The use of unitary metallic enclosures, however, places an additional burden upon the arc extinguishing devices. Although a certain amount of flame may be tolerated within a substation building, the issuance of flame from an arc extinguisher within a metallic enclosure would produce disastrous results. Furthermore, the problem of flame suppression becomes more acute in power substation applications in that power companies frequently suspend their high voltage lines upon the same poles with and above the low voltage lines. It sometimes occurs that during a storm or other adverse weather conditions, the high voltage lines are brought into direct contact with the low voltage lines, thereby subjecting the low voltage breaker to many times its normal voltage rating.

The main object of my invention is to provide an arc extinguishing device for an air circuit breaker which will effectively suppress the arc flame even though the breaker is subjected to voltages considerably above its rating.

A further object of my invention is the provision of an arc extinguishing device for an air circuit breaker having a higher interrupting

capacity but having considerably smaller dimensions than the devices heretofore known in the art.

Another object of my invention is the provision of an arc extinguishing device for air break circuit interrupters which is capable of withstanding a sustained arc of voltage considerably higher than its normal rating without impairing its interrupting ability thereafter.

A more specific object of my invention is the provision of an arc extinguisher for an air break circuit interrupter which employs an enclosure substantially completely surrounding the breaker contacts and in which arc deionization is accomplished by driving the arc into a plurality of closely spaced metallic plates separated by insulating members so arranged as to provide a narrow undulated arc passage of considerable length between adjacent plates, and into which passages short sections of the arc initially drawn are adapted to be moved.

Other objects and advantages relate to details of the arc extinguishing structure and will appear more fully in the following description when taken in connection with the accompanying drawings in which:

Figure 1 is a side elevation view of a circuit interrupter showing an embodiment of my invention;

Fig. 2 is a side elevation view partially in section showing the arc extinguishing device of my invention on a somewhat enlarged scale as that shown in the assembly view of Fig. 1;

Fig. 3 is a cross-sectional view of the arc extinguishing device of my invention taken along the line III—III of Fig. 2;

Fig. 4 is an exploded perspective view showing a section of the deionizing plate structure of the arc extinguishing device of my invention;

Fig. 5 is a side elevation view, partially in section, of a modified form of arc extinguishing device, and

Fig. 6 is a cross-sectional view of the arc extinguishing device of Fig. 5 taken along the line VI—VI of that figure.

Referring to Figure 1 of the drawings, the reference numeral 10 designates a pair of frame members between which the contact mechanism on the circuit interrupter is disposed. The contact mechanism in this instance comprises a fixed contact support 12 secured between the frame members 10 by the bolts 14. The contact support 12 carries a fixed contact 16 which may be secured thereto by means of a screw 18 as shown. Adapted to cooperate with the fixed contact 16

is a movable contact 20 carried by a contact support 22 which in turn is pivotally supported at 24 to a contact carrying arm 26. Contact arm 26 is pivotally supported between the frame members 10 by shaft 28. The contact support 22 is provided with a downwardly extending projection 30 to which one end of a compression spring 32 is secured for the purpose of biasing the movable contact 20 into engagement with the fixed contact 16. The other end of the spring 32 preferably engages the shaft 28. Connection from the contact support 22 to a line terminal 34 is made by means of a flexible shunt 36.

The movable contact 20 is actuated to the open and closed position through a link member 38 pivoted at its upper end to the contact arm 26 and at its lower end to an actuating arm 40, which arm is pivoted to the frame members 10 at 42. The actuating arm 40 is provided at its outermost end with a roller 44, which, in turn, is adapted to engage a cam actuating mechanism indicated at 46. The moving contact 20 is biased to the open position by means of a compression spring 48 bearing upon the actuating arm 40.

The open position of the circuit interrupter is indicated by the dotted lines showing the outline of the movable contact 20, a designation of the associated parts for moving the contact being omitted for the sake of clarity.

An arc established between the fixed contact 16 and the movable contact 20 is adapted to be received by the arc extinguishing device generally designated at 50 in Fig. 1 and more specifically illustrated in Figs. 2 to 4, inclusive. The arc extinguishing device 50 comprises a pair of spaced side wall members 52 of insulating material having a lower triangular portion 54 provided with aligned openings 56 for receiving a support bolt 58, the outer ends of which are adapted to engage suitable notches 60 provided in the frame members 10 as shown in Fig. 1. The upper portion of the arc extinguishing device 52 is provided with a slotted member 62 secured between the side wall members 52 by a bolt 64. The upper or slotted portion of the member 62 is adapted to be brought into registration with a clamping bolt 66 secured to a fixed portion 68 of the circuit breaker frame and is provided with a wing nut 70 for clamping the arc extinguishing device into position. By removing the wing nut 70 the arc extinguishing device 50 may be rocked in a clockwise direction about the bolt 60 until the upper edges of the side walls 52 clear the adjacent portions of the breaker structure whereupon the arc extinguishing device may be lifted from the notches 60 in the frame members 10. This construction permits easy removal and replacement of the arc extinguishing device so as to obtain access to the contact structure in the event such access becomes necessary.

In order to effectively extinguish the arc drawn between the contacts 16 and 20, I have provided arc deionizing means disposed between the side wall members 52 which will now be described. Adjacent the lower side of the side wall members 52 of insulating material which, in effect, form side wall members of an arc chute, is provided a spacing member 72 of insulating material securely clamped between the side wall members 52 by means of bolts 74. Adjacent this lower spacing member 72 is placed an arc horn 76, preferably in the form of a copper plate having an upstanding projection 78 at the left-hand side thereof, which terminates adjacent the movable contact 20 when the latter is in the open circuit

position and a downwardly projecting member 79 which extends through the spacing member 72 and makes connection with the line terminal 34 by way of connector 81.

Disposed above the lower arc horn 76 are a plurality of alternate plates of conducting and insulating material. The conducting plates, which are preferably of copper, are more clearly shown in Figs. 2, 3 and 4 and designated by the reference number 80.

The plate members of insulating material are designated at 82 and are preferably of such material as horn fibre, which has suitable properties to withstand the direct action thereupon by an arc. The ends of the metallic plates 80 disposed adjacent to the contacts 16 and 20 are provided with a V-shaped arc receiving slot or notch 84.

The plate members 82 of insulating material are also provided with a V-shaped notch 86 at the left-hand end thereof and a through slot 88 of undulated form which, in reality, causes the plate member to be constituted by two separate sections. The slots 88 extending through the insulating members 82 provide an elongated arc passage of relatively constricted area between each adjacent pair of plates 80 of conducting material. Alternate insulating members 82 are reversed so that the arc passages 88 between the successive plates 80 are not in alignment except at the entrance and terminate upon alternate sides of the center line of these plates, thus providing a greater break-down surface between the discharge openings of these passages.

It will be noted that the metallic plates 80 are somewhat shorter than the plates 82 of insulating material, which would normally introduce a gap between adjacent plates of insulating material. This gap is filled in by a suitable filling member 90 of insulating material which forms a continuation of the plate 80 of conducting material. In accordance with this construction the discharge end of the arc passage 88 is completely boxed in by insulating material which, as will appear more fully hereinafter, assists in preventing the emission of flame from the discharge opening. It will also be noted from the construction as shown in Figs. 2 and 4 that the plates 82 of insulating material are of wedge shape and arranged so that the plates 80 of conducting material diverge from each other in the direction away from the contacts 16 and 20. This feature permits a more rapid flow of arc gases from the arc receiving end of the deionizing structure towards the discharge end in that the volume of the arc passages 88 increases per unit length in the direction in which the arc is adapted to be moved.

In order to hold the plates 80 and 82 in position with respect to the side wall members 52, I have provided the inside surface of each side wall member 52 with at least two undercut channels 92, and I have provided the respective plates 80 and 82 with tongues 94. The tongues 94 have an outline which conforms with the cross-section of the grooves 92 so that when the tongues are brought into registration with the grooves the respective plates are securely anchored in position.

The uppermost plate of conducting material of the deionizing structure is provided with a projection 96 which constitutes the upper arc horn 70 and terminates adjacent the fixed contact 16. Electrical connection to the arc horn 96 from the fixed contact 16 is made by means of a contact spring 98 secured to the fixed contact 16 by the screw 18. The entire stack of arc extinguishing

plates 80 and the spacing plates 82 of insulating material, as well as the lower arc horn 76 and the upper arc horn 96 are held in compression by means of two screws 100 threaded through a 5 spacing member 102 and which in turn engage a pressure plate 104 contiguous to the upper arc horn 96.

In order to prevent a blast of arc gases rearwardly of the contacts 16 and 20 into the contact 10 actuating mechanism at the instant of arc formation, I have provided a movable barrier member 95 of insulating material carried by the movable contact 20. The barrier member 95 extends between opposed recessed portions 97 within the 15 side wall member 52 and is slideable in these recesses upon movement of the contact 20 to the open circuit position so as to cause the lower end of the barrier 95 to engage the lower wall member 72 and effectively close the back part of the 20 arc extinguishing device.

Movement of the arc from the contacts 16 and 20 onto the arc horns 76 and 96, and subsequently into the plates 80, is obtained by magnetic blow-out means including a series coil 106, 25 one end of which connects to the line terminal block 108 and the other end of which terminates in a terminal block 110 which in turn is bolted to the fixed contact support 12 by means of the bolts 14. The blow-out coil 106 surrounds an iron 30 core 112, the ends of which abut against a pair of laminated yoke members 114.

The yoke members 114 extend diagonally downward and lie adjacent a pole piece 116 countersunk in each of the side wall members 52 of the 35 arc extinguishing device. The pole pieces 116 extend on either side of the contacts 16 and 20 and cover substantially the entire area occupied by the edges of the plates 80 of conducting material. It will thus be seen that the pole pieces 116 are 40 effective to distribute the flux produced by the coil 106 uniformly along the path of arc movement.

The operation of the circuit interrupter is as follows: Upon separation of the contacts 16 and 45 20, an arc is drawn therebetween which, due to the transverse flow of flux across these contacts between the pole pieces 116 as set up by the series flow of current through the coil 106, is moved laterally from the contacts 16 and 20 onto the arc horns 76 and 96. The magnetic field continues to act upon the arc driving it into the V-shaped slots 84 in the plates 80 of metallic material. When the arc reaches the closed ends of the 50 slots 84, it is split up into a plurality of short arcs. The continued action of the magnetic field upon 55 these short arcs causes each of the short arcs to be moved along its respective circuitous arc passage 88 as defined by the plates 82 of insulating material.

60 During movement of the short arcs between the conducting plates 80, deionization takes place as is well understood in the art to effect arc extinction. The provision of a relatively long and tortuous arc path for the individual short arcs permits impressing a voltage across the interrupter which is considerably in excess of the rated voltage of the interrupter without causing the arcs to be moved entirely to the end of the tortuous arc paths before being extinguished. 65 The insulated end portions 90 abutting the discharge end of the plates 80 of conducting material are also effective in extinguishing the short arcs in the event that the voltage impressed 70 across the interrupter is so severe that the short 75

arcs are driven to the end of the conducting plates.

Should the arc reach the end of the plates, it will be subjected to excessive lengthening as a result of the combined magnetic and gas blow-out action, so as to cause arc extinction before the arc is blown completely throughout the open end of the passage.

By staggering the outlet openings of the passages 88 in the manner previously described, the 10 creepage distance between adjacent openings is materially increased thereby lessening the danger of flashover exteriorly of the arc extinguishing device which may result from the escape of gases from the arc passages 88 which are not 15 completely deionized. By way of example, the particular circuit interrupting structure above described, which was designed for 2300-volt service, successfully confined a 433 ampere arc at 20,000 volts within the structure. The specific test 20 results also indicated that the arc extinguishing structure could have withstood 60 cycles or more of arcing without causing destruction of the device. Following this particular high voltage test, 25 structures of the type herein described were immediately connected in a lower voltage circuit and successfully interrupted 3630 amperes at 3170 volts within one and one-half cycles of arcing time.

In Figs. 5 and 6 I have shown a modified form 30 of arc extinguishing device which differs from the device shown in Figs. 2 and 3 in the method of forming the side wall members, the method of supporting the deionizing structure comprising the plates 80 of metallic material and the plates 35 82 of insulating material. As shown in these figures, each of the side wall members comprise two plates 120 of insulating material. The innermost plates are provided with a short plate 122 against which the metallic plates 80 and the 40 plates 82 of insulating material are brought into endwise abutment. In other words, the plates 122 serve as stop members. The plates 80 and 45 82 are held in engagement with the stop plates 122 by means of a flexible band 124 of insulating material anchored at its upper end to a spacing member 126 and secured at its lower end to a tensioning member 128 which, in turn, is pivotally secured between the side wall members 120 by a bolt 130. 50

A tensioning screw 132 is screw-threaded through the tensioning member 128 and bears upon a compression plate 134 having contiguous contact with the lower arc horn of the arc extinguishing device. The alternate plate members 55 82 of insulating material, as well as the filling in members 90, are held in proper relative position with respect to each other by a pair of flexible rods 136 which pass through the respective plate members substantially perpendicular to the 60 plane surfaces thereof.

The arc extinguishing device as shown in Figs. 5 and 6 also differs from the device previously described in that the plates 82 of insulating material are so formed that the successive tortuous 65 arc passages 88 provided thereby terminate on opposite sides of the arc extinguishing device as shown at 138, thereby further increasing the creepage distance between successive discharge openings. In this instance pole pieces 140 are 70 provided for rendering the distribution of the magnetic field more uniform and differ in arrangement from pole pieces 116 primarily in that the pole pieces 140 are not countersunk but secured to the outer surface of the side wall mem- 75

bers 120. Although this form of arc extinguishing device differs somewhat in structural details from the device shown in Figs. 2 and 3, the operation thereof is substantially the same except that the discharge of arc gases takes place on alternate sides of the device, whereas the discharge of arc gases from the successive passages 88 in the first described structure takes place from the end of the device, but in staggered relation.

Although I have shown and described a particular circuit interrupting device and specific arc extinguishing structures therefor, it is to be understood that the same is for the purpose of illustration and that changes and modifications may be made by those skilled in the art without departing from the spirit and scope of the appended claims.

I claim as my invention:

20 1. In a circuit interrupter, means for establishing an arc, a plurality of layers of spaced conducting material, means for moving said arc into said spaced layers of conducting material to produce a plurality of short arcs, and means 25 of insulating material disposed between said layers of conducting material defining a plurality of elongated narrow arc passages having at least two opposed sides enclosed by said layers of conducting material and along which said short 30 arcs are adapted to be moved, said narrow arc passages being so positioned that adjacent passages cross each other at least once throughout their length.

2. In a circuit interrupter, means for establishing an arc, a plurality of layers of spaced conducting material, means for moving said arc into said spaced layers of conducting material to produce a plurality of short arcs, and means 35 of insulating material defining a narrow wavy through arc passage between each pair of adjacent layers of conducting material, said narrow arc passages terminating alternately in laterally displaced relation with respect to each other.

3. In a circuit interrupter, means for establishing an arc, means for extinguishing said arc comprising a plurality of plates of conducting material having arc receiving notches in one end thereof, means of insulating material for spacing said plates of conducting material from each other and to provide a narrow circuitous arc passage between each pair of adjacent plates extending from the notched portion of said plates of conducting material to a distance beyond the opposite end thereof, said means of insulating 50 material being so arranged that adjacent arc passages cross each other at least once throughout their length, and means for moving said arc into said plates to produce a plurality of short arcs therebetween and to move said short arcs 55 along said narrow arc passages.

4. In a circuit interrupter, means for establishing an arc, means for extinguishing said arc comprising a plurality of plates of conducting material having arc receiving notches in one end 60 thereof, spacing members of insulating material disposed between said plates of conducting material to provide a narrow wavy arc passage between each pair of adjacent plates extending from the notched portion of said plates to the opposite end thereof, said narrow arc passages being arranged to criss-cross and terminate in staggered relation, and means for moving said arc into said plates to produce a plurality of short arcs therebetween and to move said short 65 arcs along said narrow arc passages.

5. In a circuit interrupter, arc extinguishing means comprising a plurality of spaced metallic plates having aligned notches in one end thereof, means of insulating material disposed between said plates defining a circuitous arc passage between each pair of adjacent plates, said 5 passages extending from said notches to the opposite end of said plates and terminating in free space exteriorly of said arc extinguishing means, adjacent means for establishing an arc adjacent the notched end of said plates, arc passages crossing each other at least twice throughout their length, and means for moving said arc into said plates to divide the arc into a plurality of short arcs, each of said short arcs being moved 10 along a respective passage until extinguished.

6. In a circuit interrupter, means for establishing an arc, an enclosure for receiving said arc, means within said enclosure for deionizing said arc including a plurality of narrow criss-crossed arc passages, each of said passages having a pair of arc terminal members between which a short arc may be moved, said arc passages terminating in vent openings disposed in staggered relation at the exterior of said enclosure, and means for moving the arc initially established into said deionizing means.

7. In a circuit interrupter, means for establishing an arc, an enclosure for receiving said arc, means within said enclosure for deionizing said arc including a plurality of arc passages, said arc passages having aligned converging entrance portions into which said arc is adapted to be moved, and means for moving said arc into said entrance portions to form a plurality of short 35 arcs playing in the respective arc passages, the successive arc passages providing circuitous arc paths extending a considerable distance from their entrance portions and terminating alternately on opposite sides of said enclosure.

8. In a circuit interrupter, separable contacts for establishing an arc, an arc chute having substantially parallel side walls between which said separable contacts are disposed, a pair of arc horns within said arc chute located in front of 45 said contacts and adapted to receive the arc therefrom, means disposed between said arc horns for deionizing said arc, and a barrier member movable upon separation of said contacts to effect closure of said arc chute in back of 50 said contacts.

9. In a circuit interrupter, a pair of separable contacts at least one of which is movable for establishing an arc, an arc chute having substantially parallel side walls between which said 55 pair of contacts are disposed, means within said arc chute located in front of said contacts for receiving said arc from said contacts and for deionizing the arc, and a barrier member of insulating material carried by said movable contact 60 adapted to be moved with said movable contact during contact separation to effect closure of the arc chute in back of said contacts.

10. In a circuit interrupter, means for establishing an arc, an arc chute having substantially parallel side walls between which said arc is established, means for deionizing said arc comprising alternate members of conducting and insulating material disposed transversely between 70 the side walls of said arc chute and having a V-shaped notch at the end thereof adjacent said contacts for receiving said arc, each of said members of insulating material having an undulated slot extending from the notched end to 75

- the opposite end thereof to provide a narrow elongated arc passage in which a short portion of the arc initially established is adapted to play, the slots in alternate plates of insulating material crossing each other at least once throughout their length, each of said arc passages terminating in free space exteriorly of said arc chute, and means for holding said members of conducting and insulating material in compression. 5
11. In a circuit interrupter, means for establishing an arc, an arc chute having substantially parallel side walls between which said arc is established, means for deionizing said arc comprising a plurality of plates of conducting material disposed transversely between the side walls of said arc chute and having a slot in the end thereof adjacent said arc establishing means, means for moving said arc into said slots to establish a short arc between adjacent plates of conducting material, and wedge shaped spacing members of insulating material disposed between adjacent plates of conducting material, said spacing members of insulating material providing a narrow arc passage from the slotted end of said plates to the opposite end thereof and being so arranged that said plates of conducting material diverge in a direction away from said arc establishing means. 10
12. In a circuit interrupter, means for establishing an arc, an arc chute having substantially parallel side walls between which said arc is established, the inside surfaces of said arc chute walls having at least one pair of opposed dovetail grooves formed therein, means for deionizing said arc comprising a plurality of alternate plates of conducting and of insulating material disposed transversely between the walls of said arc chute, said plates of conducting and insulating material having projecting dovetail tongues along opposite sides thereof shaped to conform with the cross section of said grooves in registration with said grooves for anchoring the plates to the side walls of said chute, said plates of insulating material having a narrow through passage between adjacent plates of conducting material, and means for moving said arc into said plates of conducting material to cause a short arc to play in each of said narrow passages. 15
13. In a circuit interrupter, a frame, a pair of contacts mounted on said frame, at least one of said contacts being movable for establishing an arc, an arc chute having substantially parallel side walls between which said pair of contacts are disposed, a barrier member of insulating material carried by said movable contact and movable with said movable contact during the opening operation of said interrupter to effect closure of the arc chute in back of said pair of contacts and means for releasably mounting said arc chute upon said frame independently of said contacts and said barrier member. 20
14. In a circuit interrupter, an arc chute having a pair of side walls, means for deionizing an arc comprising a plurality of plates of conducting material disposed transversely between the side walls of said arc chute, means for establishing a short arc between adjacent plates of conducting material, and wedge-shaped spacing members of insulating material disposed between adjacent plates of conducting material, said spacing members of insulating material providing a narrow arc passage between adjacent plates of conducting material from one end of said plates to the opposite end thereof and in which one of said short arcs is adapted to play. 25
15. In a circuit interrupter, means for establishing an arc, an arc chute having substantially parallel side walls between which said arc is established, means for deionizing said arc comprising a plurality of alternate plates of conducting and of insulating material disposed transversely between the walls of said arc chute, each opposite inner surface of said arc chute walls having at least one undercut groove therein extending in a direction substantially normal to said plates of conducting and insulating material, said plates of conducting and insulating material having tongues along the sides thereof shaped to conform with the cross-section of said grooves and projecting into said grooves for interlocking said plates with the side walls of said arc chute, said plates of insulating material having a narrow-through passage between adjacent plates of conducting material, and means for moving said arc into said plates of conducting material to cause a short arc to play in each of said narrow passages. 30
